FISH LURE

Ewell J. Harris, Sunset Mobile Homes, Rte. 3, Box 135A,
Adrian, Mich. 49221

Filed June 9, 1972, Ser. No. 263,744

Term of patent 14 years

Int. Cl. D22—05

U.S. Cl. D22—29

Fig. 2

Fig. 1

Fig. 5

Fig. 3

Fig. 4

FIG. 1 is a side view of a fish lure embodying the present invention;

FIG. 2 is a top plan view of the fish lure shown in FIG. 1;

FIG. 3 is a front view of the fish lure shown in FIG. 1;

FIG. 4 is a back view of the fish lure shown in FIG. 1;

FIG. 5 is a bottom end view of the fish lure shown in FIG. 1;

FIG. 6 is a side view similar to FIG. 1, but showing another embodiment of the present invention having a pair of wings;

FIG. 7 is a top plan view of the fish lure shown in FIG. 6;

FIG. 8 is a front view of the fish lure shown in FIG. 6;

FIG. 9 is a back view of the fish lure shown in FIG. 6; and

FIG. 10 is a bottom end view of the fish lure shown in FIG. 6.

I claim:

The ornamental design for a fish lure, substantially as shown and described.
